L. H. PHILLIPS

ELECTRIC SWITCH

Filed May 9, 1925

Fig. 1.

UNITED STATES PATENT OFFICE.

LEWIS HALL PHILLIPS, OF ATLANTIC HIGHLANDS, NEW JERSEY.

ELECTRIC SWITCH.

Application filed May 9, 1925. Serial No. 29,121.

The present invention relates to electric switches, and has particular reference to multiple switches.

An object of this invention is to provide a device of this character whereby a plurality of circuits may be controlled or operated through a central circuit selector.

Another object of this invention is to provide a device through which the accidental closing of an undesired circuit can not be accomplished.

A further object of this invention is to provide a switch having a central turn-plate which may be revolved upon its axis to a pre-determined point to close a particular circuit.

The above and various other objects and advantages of this invention will in part be described in, and in part be understood from, the following detailed description of the present preferred embodiment of the invention, the same being illustrated in the accompanying drawing, wherein:

Fig. 1 is a detail top plan view of a device constructed according to the present invention.

Fig. 2 is a transverse vertical section taken substantially through the center of the switch and showing the interior construction of the same.

Fig. 3 is a fragmentary detail enlarged view of one side of the double throw switch at its pivoted end.

Fig. 4 is a transverse section taken substantially through the center of one of the movable terminals.

Fig. 5 is a detail top plan view of the same, and

Fig. 6 is a fragmentary detail top plan view of the central portion of the base and showing in detail the collector rings through which current from the selected circuit is adapted to pass.

Referring to the drawing, 10 designates a base which may be constructed of any suitable insulating material, and upon the central portion of which is mounted an insulating ring 11. The ring 11 has a plurality of notches 12 for purposes which will herein-after be more fully described.

The base 10 has a central opening 13 extending downwardly in substantially the same plane as the inner side of the ring 11. The opening 13 is adapted to receive a turn-plate 14 the axis of which is mounted upon a ball bearing or the like pivot 15. The piv-

ot 15 is comprised of an upstanding pivot which is mounted upon a ball race 16 or the like at its lower end, and is secured at its upper end to the turnplate 14 by a nut 17 or the like. A complementary ball race 18 is mounted in the base 10 in substantially the center of the opening 13, and a pivot bolt 19 or the like extends upwardly through the races 18 and 16. The opposite ends of the bolt 19 are preferably secured by nuts 20 so that the turnplate 14 will turn easily upon the balls 21 which are mounted between the complementary ball races 16 and 18.

A double throw knife switch having connecting bars or rods 22 and 23 which are held at their outer ends in spaced relation to each other by an insulating bar 24 upon which is mounted a handle 25 or the like, is pivotally mounted upon the turnplate 14, being secured thereto by a pair of straps 26 or the like. A pair of offset terminals 27 and 28 are attached to the lower side of the turnplate 14 by a bolt 29 or the like which is secured at its upper side to the strap 26, thus affording a direct connection between the terminals 27 and 28 and the connecting bars 22 and 23.

The terminals 27 and 28 are identical in construction, comprising a casing 30 which extends downwardly from a base or body 31. The casing 30 has a downwardly extending opening 32 in which is mounted a helical expanding spring 33 or the like. The upper end of the spring 33 engages the upper end of the opening 32, and at its lower end engages a contact pin 34 or the like, the pin 34 extending downwardly through the opening 32. A cap 35 is threaded upon the outer side of the lower end of the casing 30, and maintains the pin 34 in axial relation to the opening 32.

The lower ends of the contact pins 34 yieldably engage the upper surfaces of an inner collector or contact ring 36 and an outer collector ring 37. The inner ring 36 is connected by a wire or the like 38 to a terminal 39 which is mounted upon the base 10. The outer ring 37 is likewise connected by wire 40 to a terminal 41 which is secured to the base 41 at opposite sides to the terminal 39.

In each of the openings 12 there is a spring contact member 42 which is secured to the base 10, and each contact member 42 is connected to a terminal 43 by a wire 44 or the like. Each pair of contacts 42 consti-

tutes a separate circuit which may be selected by simply swinging the turnplate 14 and the knife switch into the desired position.

In order to prevent the accidental closing of an undesired circuit, the contact bars 22 and 23 are notched at their pivoted end as illustrated by 45 in Fig. 3. A stop pin 46 is secured to the pivots 26 so that when the bars 22 and 23 are swung upwardly and outwardly the notched portion 45 comes into contact with the stop pin 46. The switch is then in open or off position.

The knife switch is normally in open or off position and in order to operate the desired circuit the turnplate 14 and the switch is turned upon the axis or pivot 15 until the contact arms 22 and 23 are substantially above the desired pair of contact members 42. The contact bars 22 and 23 are then pressed downwardly until they are yieldably held between the selected pair of contacts 42. The desired circuit is then closed.

It is, of course understood that various changes and modifications may be made in the details of construction and design of the above specifically described embodiment of the invention without departing from the spirit thereof, such changes and modifications being restricted only by the scope of the following claims.

What is claimed is:

1. A multiple electric switch comprising a base, a ring mounted upon the base and having a series of paired openings therethrough, a double armed knife switch mounted upon said base, means for turning said switch upon said base, said turning means being mounted in spaced relation to the base, a plurality of contacts mounted within said paired openings, means for connecting each pair of said contacts to a selected circuit, yieldable wiping contacts secured to said turning means and depending from said double armed knife switch, an inner and an outer circular terminal mounted upon said base and beneath said switch, and means for connecting said circular terminals to a source of electric energy.

2. A multiple electric switch comprising a base, a ring mounted upon the base and having a series of paired openings therethrough, a pair of contact arms, a turnplate pivotally mounted upon said base and within the ring, said turnplate being mounted in spaced relation to the base, means for mounting said contact arms upon said turnplate, a plurality of spring contacts secured to said base and within said paired openings, means for connecting said spring contacts with selected circuits, a pair of depending yieldable wiping contact arms secured to said turnplate and said pair of contact arms, a pair of ring terminals secured to said base, said ring terminals being adapted to be wiped by said wiping con-

tacts, and means for connecting said ring terminals to a source of electric energy.

3. A multiple electric switch comprising a base, a ring mounted upon the base and having a series of paired openings therethrough, a turnplate pivotally mounted upon said base and in spaced relation thereto, a pair of contact arms mounted upon said turnplate, a plurality of spring terminals mounted upon said base and within said paired openings, means for connecting said spring terminals to selected circuits, a pair of yieldable wiping contact arms secured to said turnplate and said pair of contact arms, an inner and an outer ring terminal positioned upon said base and being adapted to be engaged by said wiping contact arms, and means for connecting said ring terminals to a source of electric energy.

4. A multiple electric switch comprising a base, a ring mounted upon the base, said ring having a plurality of paired openings therethrough, a double armed knife switch pivotally mounted upon said base and within the ring, a pair of ring terminals mounted upon the base and beneath said switch, yieldable wiping contacts depending from said switch and adapted to wipe said ring terminals for energizing said switch arms, means for connecting said ring terminals to a source of electric energy, a plurality of spring contacts mounted upon the base and within said paired openings, and stop means for controlling the outward movement of the switch arms.

5. A multiple electric switch comprising a base, a ring upon the base, said ring having a plurality of paired openings, therethrough, a pivot mounted upon the base and within said ring, a turnplate on said pivot and adapted for free turning movement within said ring, a double armed knife switch mounted upon said turnplate, an inner and an outer ring terminal secured to said base, means for connecting said terminals to a source of electric energy, a pair of yieldable terminals secured to said switch arms and depending from the lower side of said turnplate, said yieldable terminals at their lower ends wiping said inner and outer ring terminals for energizing said switch arms, a plurality of spring contacts secured to said base and within said openings in said ring, and means for connecting said spring contacts to selected circuits.

6. A multiple electric switch comprising a base, a ring upon the base, said ring having paired openings therethrough, a turnplate pivotally secured to said base and within said ring and adapted to swing upon its pivot in spaced relation to the base, a plurality of switch arms mounted upon said turnplate and adapted to turn therewith, a plurality of yieldable terminals depending

from said turnplate and connected to said switch arms, said yieldable contacts comprising a base, a casing depending from the base, said casing being threaded at its lower 5 end, a spring in the casing, a pin engaging the lower end of said spring, and a cap for holding the pin in position, a plurality of ring terminals mounted upon said base and beneath said turnplate, said yieldable terminals being adapted to wipe said ring terminals, means for connecting said ring terminals to a source of electric energy, and a plurality of spring contacts mounted upon 10 said base within said openings in said ring. 15 7. A multiple electric switch comprising a base, said base having a circular recess therein, a ring mounted upon the base and about said recess, said ring having a series of paired openings therethrough, a pivot mounted upon said base and within said recess, a turnplate on said pivot and adapted for free turning movement within said recess and in spaced relation to the base, a double armed knife switch mounted upon 20 said turnplate, an inner and an outer ring terminal secured to said base within said recess, means for connecting said terminals to a source of electric energy, a pair of yieldable terminals secured to said switch arms and depending from said turnplate, 25 said yieldable terminals at their lower ends wiping said inner and outer ring terminals for energizing said switch arms, a plurality of spring contacts secured to said base and within said openings in said ring, and means 30 for connecting said spring contacts to selected circuits.

LEWIS HALL PHILLIPS.
